UNITED STATES PATENT OFFICE

147,436

DESIGN FOR A TEAPOT

Rolf John Falk, Zanesville, Ohio, assignor to
Shawnee Pottery Company, Zanesville, Ohio, a
corporation of Ohio

Application April 20, 1946, Serial No. 128,808

Term of patent 14 years

(Cl. D44—26)

To all whom it may concern:

Be it known that I, Rolf J. Falk, a citizen of the United States of America, residing at Zanesville, in the county of Muskingum and State of Ohio, have invented a new, original, and ornamental Design for Teapot, of which the following is a specification, reference being had to the accompanying drawings, forming a part thereof, wherein:

Fig. 1 is a front elevation of a teapot illustrating my new design;

Fig. 2, a rear elevation; and

Fig. 3, a top plan view.

I claim:

The ornamental design for a teapot, as shown.

ROLF JOHN FALK.
